TEMPERATURE AND EARTHQUAKE RESPONSIVE ELECTRIC SWITCH

Timothy J. Sullivan, Butte, Mont., assignor to Sullivan Valve and Engineering Company, Butte, Mont., a corporation of Montana

Application October 3, 1957, Serial No. 687,944

3 Claims. (Cl. 200—61.48)

This invention relates generally to an electric switch, and more particularly to an electric switch which is responsive both to excessive temperatures and to shocks caused by earthquakes and the like.

In many industrial installations it is desirable to include switch means in the electrical power supply of associated electrical equipment which will interrupt the electrical service upon the presence of excessive temperature caused by fire or overheating of equipment or upon excessive shocks, vibration or impacts caused by earthquakes, explosions and the like. It is well known in the prior art to use separate switch units for controlling an electrical circuit, one unit being responsive to earthquake shocks and the other unit being responsive to temperature. The present invention was developed to provide a single switch unit which is responsive to both excessive temperature and to shocks and vibration.

Thus the primary object of my invention is to provide an electric switch which is responsive to both excessive temperature and to shocks caused by earthquakes and the like.

A more specific object of my invention is to provide an electric switch having a movable contact element held into engagement with a stationary contact by means of a pivotally-mounted shock-responsive member in combination with a temperature-responsive member arranged to actuate said shock-responsive member to cause disengagement of the movable element from the stationary contact.

Other objects and advantages of my invention will become more apparent from a study of the following specification when considered in conjunction with the accompanying drawings, in which:

Fig. 1 is a plan view of my temperature and earthquake responsive switch;

Fig. 2 is an elevational view of the switch in its preset, closed position;

Fig. 3 is an elevational view of the switch in its open position; and

Fig. 4 is an end elevational view of the housing and its cover.

Referring now more particularly to the drawings, a switch unit 1 is rigidly secured within the metal housing 2 by means of bolts 3. Lead-in wires 4, 5 and 6 from the cable C are connected to the switch contact terminals 7, 8 and 9 respectively. Terminals 7 and 8 are connected by means of internal leads 7' and 8' to the stationary switch contacts 7" and 8", and terminal 9 is connected by lead 9' to the movable contact 11 which is pivotally mounted within the switch unit 1 about fixed pivot 10. The movable contact 11 is positioned between the stationary contacts 7" and 8" and when the contact 11 is in its lower position as shown in Fig. 2, electrical contact will be made with contact 8" and when the contact is in its upper position as shown in Fig. 3, electrical contact will be made with contact 7".

Compressed coil spring 12 positioned intermediate the movable contact element 11 and the bottom 2a of the

housing 2 tends to urge the movable contact element 11 upwardly into contact with the stationary contact 7".

Rigidly bolted to one wall of the housing 2 is a bracket 13 having a lateral portion which extends above the movable contact element 11. Bracket 13 has a socket seat 13a therein upon which is rotatably supported ball 14 rigidly connected to retaining shaft 15 intermediate its ends. At the upper extremity of shaft 15 is secured a spherical weight member 16 and the lower extremity 15a of the shaft 15 is adapted to be seated upon the electrically insulated vertical projection 11a of the contact element 11 when the shaft is in its vertical position to hold the movable contact element 11 in engagement with stationary contact 8" against the upward biasing force of compressed spring 12 as shown in Fig. 2.

Slidably mounted in aperture 2c in one wall of the housing 2 is the actuating rod 17 having an enlarged head portion 17a at one end thereof within the switch housing and a hooked portion 17b at the other end externally of the switch housing. Compressed spring 18 positioned about the rod 17 intermediate the enlarged head portion 17a and the wall of the housing 2 tends to bias the rod 17 toward the shaft 15 to knock the lower extremity of shaft 15 from the vertical projection 11a as will be explained in greater detail below.

Rigidly bolted to the housing 2 is a lateral bracket 19 having a hooked portion 20 at its outer extremity. Removably connected at one end to hooked portion 17b of rod 17 and at the other end to hooked portion 20 of bracket 19 is a temperature-responsive fusible link element 21. The fusible link element serves to maintain the rod 17 in its retracted position against the tension of spring 18 as shown in Fig. 2.

The switch housing 2 is mounted to the fixed support 23 (which may be a structural portion of a building, heating unit, gas boiler or the like) by means of brackets 22. A cover 2b is removably secured to the housing 2 and constitutes the top and front wall of the housing. Removal of the cover provides access to the housing for resetting the switch as will be explained in greater detail below.

In making the electrical connections of the switch, input leads 5 and 6 are connected in series with the power line of the equipment to be controlled and input lead 4 is connected to a suitable alarm circuit which provides visible or audible indication of the opening of the switch power contacts.

The operation of the earthquake and temperature responsive switch may now be set forth in detail.

When the switch housing 2 is secured to the support 23 by brackets 22 and the cable conductors 4, 5 and 6 are connected to terminals 7, 8 and 9 respectively, the weight member 16 is lifted in its uppermost position as shown in Fig. 2 and retaining shaft 15 is pivoted about ball 14 and socket 13a to its vertical position. The lower extremity 15a of shaft 15 engages projection 11a and holds movable contact 11 into engagement with stationary contact 8" against the upward biasing force of compressed coil spring 12. Thus a completed circuit is established between conductors 5 and 6 through internal lead 9', movable contact 11, stationary contact 8", and internal lead 8'. Since conductors 5 and 6 are connected in series with the electrical power supply to the associated electrical equipment, normal functioning of the equipment will be established upon throwing the main power switch. Fusible element 21 connected between the hook 20 of stationary bracket 19 and the projection 17b of actuating rod 17 serves to maintain the rod in its retracted position shown in Fig. 2 against the biasing action of compressed coil spring 18.

Upon the occurrence of shock to the support 23, as caused by an earthquake, blasting of explosives, excessive

vibration or the like, the center of gravity of weight member 16 will be moved from its vertical position above the pivotal axis of ball 14 in socket seat 13a, and lateral downward movement of weight member 16 will cause retaining shaft 15 to pivot from its vertical orientation about the ball and socket connection to an oblique orientation as shown in Fig. 3. The lower extremity 15a of shaft 15 will be disengaged from the projection 11a, and movable contact 11 will be pivoted upwardly about pivot 10 from stationary contact 8" and into engagement with stationary contact 7" by the vertical explosion of coil spring 12. Thus the electrical connection between power conductors 5 and 6 will be broken, and the alarm circuit containing conductor 4 will be closed through internal lead 9, movable contact element 11, stationary contact 7", and internal lead 7'.

Upon the occurrence of excessive temperature caused by fires, overheating of equipment and the like, when the switch is in the closed position of Fig. 2, the temperature-responsive fusible link 21 will be broken and spring 18 will expand to cause actuating rod 17 to move toward the vertical retaining shaft 15. The enlarged head portion 17a of the rod 17 comes into engagement with the shaft 15 and the force of spring 18 knocks the lower extremity of the shaft 15a from the projection 11a so that movable contact element 11 is free to be pivotally moved upwardly out of engagement with stationary contact 8" and into engagement with the alarm circuit stationary contact 7" by expansion of coil spring 12. It is important to point out that the jar or shock imparted to the portion of shaft 15 below the universal pivotal mounting of ball 14 in socket 13a is imparted to the weight member 16 through the shaft so that the momentum of the weight member 16 about the ball and socket pivot axis will assist in causing pivotal movement of the retaining shaft out of engagement with projection 11a to release movable contact member 11.

The structural arrangement of the switch is such that the actuation can be made to be quite sensitive, since the weight of the member 16 is great with respect to the weight of the shaft 15 and ball 14, and the seating of the ball 14 upon the socket 13a may be made to be very delicate since the upward force upon the lower extremity 15a of the shaft by the projection 11a serves to steady the shaft 15 in its vertical orientation.

In order to reset the switch after it has been opened due to shock or vibration, the cover 2b is removed and the weight member 16 is pivotally raised to the vertical position so that the lower shaft extremity 15a will contact projection 11a to urge the movable contact 11 into engagement with stationary contact 8".

To reset the switch after it has been opened after breakage of the fusible link 21 upon the presence of excessive temperature, the broken parts of the link are removed and a new link is connected at one end to projection 17b of rod 17. The rod 17 is then pulled to the right in Fig. 3 to compress the spring 18 and the other end of the link is hooked upon the stationary hook 20. Cover 2b is then removed and the weight member 16 is pivoted upwardly until the lower shaft extremity 15a again engages projection 11a to urge movable contact 11 into engagement with stationary contact 8'.

Thus it is apparent that my invention provides a switch which is extremely sensitive to both temperature and

shock and which has a durable, trouble-free arrangement constructed from a minimum of relatively inexpensive, rigid parts.

5 While in accordance with the provisions of the patent statutes I have illustrated and described the best form of embodiment of my invention known to me, it will be apparent to those skilled in the art that other modifications can be made in the apparatus disclosed without deviating from my invention as defined in the following 10 claims.

I claim:

1. An electric switch comprising a housing, a stationary contact in said housing, a movable contact pivotally mounted in said housing above said stationary contact, electrical conductors connected to said contacts, spring means biasing said movable contact away from said stationary contact, impact-responsive means normally maintaining said movable contact into engagement with said stationary contact in opposition to the biasing force of said spring means and adapted to release said movable contact from said stationary contact upon the importation of impact to said housing, said impact-responsive means comprising a fixed member secured to said housing above said movable contact, said member having a circular opening extending therethrough the peripheral edge of which forms a universal ball socket, a ball member rotatably supported upon said ball socket, a retaining shaft secured intermediate its ends to said ball member, a weight member secured to the upper end of said retaining shaft, the lower portion of said shaft extending through said opening in engagement with said movable contact when the shaft is in a vertically-balanced position to maintain said movable contact in electrical engagement with said stationary contact, and temperature-responsive means for actuating said impact-responsive means to release said movable contact from said stationary contact upon increase of ambient temperature above a predetermined value comprising an actuating rod slidably mounted in said housing adjacent said impact-responsive means, spring means urging said rod axially in a direction to cause engagement thereof with the lower portion of said retaining shaft to impart an impact to said shaft, and a temperature-responsive fusible link element connected at one end to said housing and at the other end to said rod to maintain said rod in a retracted position out of engagement with said retaining shaft.

2. An electric switch as defined in claim 1 wherein said actuating rod extends through one wall of said housing and said fusible link element is mounted externally of said housing.

3. An electric switch as defined in claim 1 and further including a second stationary contact in said housing on the other side of said movable contact from said stationary contact, said movable contact spring biasing means tending to urge said movable contact in a direction to cause engagement thereof with said second stationary contact.
